UNITED STATES PATENT OFFICE.

JACOB AARON HERMAN, OF NEW YORK, N. Y.

DRESS.

1,079,552.

Specification of Letters Patent.

Patented Nov. 25, 1913.

Application filed May 17, 1912. Serial No. 697,962.

To all whom it may concern:

Be it known that I, JACOB AARON HERMAN, a citizen of the United States, residing at New York city, in the county and State of 5 New York, have invented certain new and useful Improvements in Dresses, of which the following is a specification.

My invention relates to what is known as a princess dress, in which the waist and skirt 10 portions are made in one piece, and the object of my invention is a construction in which the waist line can be adjusted to fit the wearer without adjusting any other portion of the dress.

15 The accompanying drawings will serve to illustrate my invention, in which—

Figure 1 is a rear elevation showing the dress adjusted to a wearer having a small waist; Fig. 2 is a similar view, showing the 20 dress adjusted to a wearer having a large waist, with the back placket flap let down. Fig. 3 is a similar view, with the back placket flap in position. Fig. 4 is a transverse section taken on the line X—X of Fig. 25 1. Fig. 5 is a transverse section taken on the line X—X of Fig. 3. Fig. 6 is a front elevation of the fastening braid.

In the drawings, the front of the dress 5 is indicated by a single line, which is connected to the sides of the dress 6. The shape 30 of the front and sides of the dress may be as is usual. Connected to the sides at the back, are back portions 7, which are substantially straight along the meeting edge 35 8 to the waist line, and then curved outwardly and downwardly as shown at 9, toward the side portions 6. Arranged to overlie the opening indicated at 10, is a back 40 placket flap 11, which forms the top of the back of the skirt below the waist line. Arranged at the waist line starting from the sides and carried inward, is a woven braid 45 12, having openings 13 therein. The meeting edge 8 of the parts 7, is provided at the top and bottom with fastening devices 14 and 15, which may be hooks. When the dress is put on, the fastening device 14 at the top is secured. The fastening device 15 at the waist line is then carried along the 50 line of the braid until the dress fits snugly at the waist, and is then secured to the braid. If the waist of the wearer is small, the fastening device is carried to the position substantially as shown in Fig. 1; if large, to the position shown in Fig. 2, and then secured, after which the back placket flap

11 is turned upward and secured in the braid 12 by means of the hooks 16.

17 indicates in dotted lines, a belt which may be applied at the waist line, secured in 60 front or back.

Having thus described my invention, I claim:

1. A dress comprising a front portion, side portions, duplicate back portions substantially straight along the meeting edges from the neck to the waist line, and curved outwardly and downwardly from the waist line toward the side portions, a back placket flap portion adapted to cover the opening in 70 the back of the skirt portion of the dress below the waist line, and means for adjusting the back portions as regards each other along the waist line so that the size of the waist of the dress shall conform to that of 75 the wearer.

2. A dress comprising a front portion, side portions, duplicate back portions extending from the shoulder seams to a point below the waist line and substantially straight 80 along the meeting edges from the neck to the waist line, and curved outwardly and downwardly from the waist line toward the side portions, a back placket flap portion formed integrally with the back breadth of the dress 85 and adapted to cover the opening in the back of the skirt portion of the dress below the waist line, and means for adjusting the back portions as regards each other along the waist line and for securing the back 90 placket flap at the waist line so that the size of the waist of the dress shall conform to that of the wearer.

3. A dress comprising a front portion and side portions continuous from the shoulder seams to the bottom of the dress, duplicate back portions continuous from the shoulder seams to a point below the waist line, said back portions substantially straight along the meeting edges from the neck to the waist line, and curved outwardly and downwardly from the waist line toward the side portions, a back placket flap portion adapted to cover the opening in the back of the skirt portion of the dress below the waist line, a braid 100 provided with openings located at the waist line, a hook at the lower edge of one of the back portions at the waist line adapted to co-operate with said braid, and hooks on the upper edge of the back placket flap portion 105 adapted to co-operate with said braid, whereby the size of the waist of the dress may 110

be adapted to the size of the waist of the wearer.

4. A single piece dress adjustable to various sizes of the wearer at the waist line, comprising a front portion, side portions, duplicate back portions substantially straight from the shoulder seams to the waist line, and adapted to meet from the back of the neck to the waist line at the back 10 and to be overlapped if required to conform to the size of the waist of the wearer and curved outwardly and downwardly from the waist line toward the side portions, a back placket flap portion adapted to cover the opening at the back of the skirt portion, a braid having spaced openings located at the waist line, and means connected to one of the back portions and means connected to the flap portion, said means adapted to coact 15 with the braid to adjust the size of the waist of the dress to the size of the waist of the wearer.

5. A so-called princess dress, comprising an integral front portion, integral side portions, a back panel consisting of two pieces 25 continuous from the neck to a point below the waist line, said pieces substantially straight along their meeting edges to the waist line, and curved outwardly and downwardly from the waist line to the side portions, a back panel continuous from the waist 30 line to the bottom of the skirt, said back

panel formed as a placket flap at its upper portion but secured at its outer edges to the side portions from a point at the bottom of 35 the flap to the bottom of the skirt, a perforated braid located at the waist line, means secured to one of the back portions and means secured to the flap portion adapted to coöperate with said braid, whereby the 40 size of the waist line of the dress may be adjusted to the size of the waist of the wearer.

6. In combination with a dress, a woven braid located at the waist line, together with 45 means secured to the dress and adapted to coöperate with the braid to adjust the size of the waist line of the dress to the size of the waist of the wearer.

7. In combination with a dress, a woven 50 braid located at the waist line, consisting of spaced longitudinal members and spaced vertical members, together with means secured to the dress and adapted to coöperate with the braid to adjust the size of the 55 waist line of the dress to the size of the waist of the wearer.

In testimony whereof, I affix my signature, in the presence of two witnesses.

JACOB AARON HERMAN.

Witnesses:
